UNITED STATES PATENT OFFICE

HAROLD C. VAISEY, OF ROCHESTER, NEW YORK, ASSIGNOR TO HICKOK MANUFACTURING COMPANY, OF ROCHESTER, NEW YORK, A CORPORATION OF NEW YORK

DESIGN FOR A SUSPENDER-END TOP LINK

Application filed September 9, 1929. Serial No. 32,698. Term of patent 3½ years.

To all whom it may concern:

Be it known that I, HAROLD C. VAISEY, a citizen of the United States, residing at Rochester, in the county of Monroe and State of New York, have invented a new, original, and ornamental Design for a Suspender-End Top Link, of which the following is a specification, reference being had to the accompanying drawing, forming part thereof.

In the drawing:

Fig. 1 is a face view of a suspender-end top link showing my new design; and

Fig. 2 is an edge view thereof.

I claim:

The ornamental design for a suspender-end top link, as shown.

HAROLD C. VAISEY.
